DESIGN FOR A CIGARETTE REST AND EXTINGUISHER

James T. Murphy, Boston, Mass.

Application February 21, 1945, Serial No. 118,070

Term of patent 7 years

(Cl. D85—2)

To all whom it may concern:

Be it known that I, James T. Murphy, a citizen of the United States, residing at 30 Marlboro Street, Boston, county of Suffolk, State of Massachusetts, have invented a new, original, and ornamental Design for a Cigarette Rest and Extinguisher, of which the following is a specification, reference being had to the accompanying drawing, forming a part thereof.

Fig. 1 of the drawing is a perspective view of a cigarette rest and extinguisher showing my new design;

Fig. 2 is a rear end view of the same.

I claim:

The ornamental design for a cigarette rest and extinguisher, as shown.

JAMES T. MURPHY.
